UNITED STATES PATENT OFFICE

2,489,165

DRAFTING BOARD

Raymond D. Smith, Madison, Wis.

Application June 25, 1946, Serial No. 679,133

1 Claim. (Cl. 45—131)

1

My invention refers to a "drafting kit" and it has for its primary object to provide a simple, inexpensive drafting apparatus, comprising a rectangular board having a pair of right angled raised track-strips upon two converging straight edges of the board, the same being stopped off at the associated board corner to form a throat.

The board is associated with an L-shaped flat right angle unit, having arms terminating with different end angles, and various scales upon the edges thereof, together with a series of apertures forming open geometrical figures for tracing.

With these two units and proper manipulation of the flat armed angle, all machine working drawings, or other illustrations, may be made with minimum lost motions. Hence, the two-piece drafting unit will eliminate the necessity for an elaborate set of drawing instruments and also much valuable time in shifting from one instrument to the other.

A further object of my invention is to provide the track-strips with spring controlled clamps for attaching drawing paper of a variety of sizes to the board, whereby the margins of the drawing paper are not mutilated by tacks, glue strips, or the like.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Fig. 1 represents a plan view of a drawing apparatus embodying the features of my invention.

Fig. 1a is an edge view of the same.

Fig. 2 is a face view of the apparatus upon a reduced scale illustrating in dotted lines various positions that may be assumed by the L-shaped angle.

Fig. 3 is a plan view of a group of different sized sheets of paper which may be affixed to the board.

Fig. 4 is a diagrammatic face view of a circle which may be formed by one of the templet apertures.

Fig. 5 is a similar view of a hexagon.

2

Fig. 6 is a similar diagrammatic view illustrating a quarter circle merged into right angle lines, which may be described through a templet aperture in conjunction with lines ruled by the angle.

Fig. 7 is an enlarged sectional elevation through the drawing board track-strip and spring clamping mechanism, the section being indicated by line 7—7 of Fig. 11.

Fig. 8 is a detailed side elevation of the board track-strip and spring clamping mechanism.

Fig. 9 is a fragmentary end elevation of the board track-strip and spring for gripping the paper.

Fig. 10 is a plan view of said paper gripping spring, particularly illustrating a locking slot associated with a knurled head; and

Fig. 11 is a plan view of the spring clamping mechanism and track-strip.

Referring by characters to the drawings, B indicates a rectangular drawing board formed by a series of fiber laminations. Riveted or otherwise secured thereto is a pair of the converging and raised track-strips G, the same being stopped off a predetermined distance from the associated corner of the board to form a clear angle throat B'.

As best illustrated in Fig. 8 of the drawings, the inner portion of the track-strip is cut away to form a paper receiving recess, which recess, as indicated in dotted lines in Fig. 1 of the drawings, extends from end to end of either track-strip G.

As shown in Fig. 1 of the drawings, the board has fitted thereto a sheet of drawing paper A, the converging edges of which are tucked under the recess of the track-strips. These edges of the paper are firmly clamped to the drawing board by U-shaped leaf springs seated under the track-strip, the said springs terminating at their inner free ends with downwardly extended teeth C, which teeth pass through apertures in the track-strips, as best illustrated in Figs. 7 and 8 of the drawings. It is understood, in this exemplification of my invention, one clamping spring for each track-strip is utilized.

As indicated in Figs. 7, 8 and 10 of the drawings, the upper face of each spring is provided with a keyhole slot D for interlocking engagement with a rib J extending downwardly from the hub of a knurled locking button N.

The locking button N is loosely mounted upon a stud N' which extends upwardly from the board and through the track-strip, spring slot, and head, the same being held in position upon the 55 stud by an end cap upon said stud N'.

As best shown in Fig. 11 of the drawings, the upper face of the rotary button N is formed with a line Q extending therethrough, which line indicates the position of the rib J. The rib, as shown in Figs. 8 and 11, is crosswise of the spring. Hence, the spring tooth C, as shown in Figs. 8 and 11, is in a depressed position to secure the paper firmly.

As shown in Fig. 7 of the drawings, the rib J, of the head, is in alignment with the spring and keyhole slot D therein, whereby the tooth C of the spring is freed from the board.

While I have illustrated and described the board as built up from laminations, it is obvious that said board and track-strips may, in some instances, be fabricated from any suitable material such as plastic, or the like, in which case the track-strips G may form an integral part of the board, without departing from the spirit of my invention.

As illustrated, the board may also be provided with rubber pads P for holding the same against slippage and also for the purpose of protecting the face of a desk when the board is shifted thereabout.

As shown in Fig. 1 of the drawings, I provide an L-shaped flat angle R formed with right angle arms, the same being constructed from any suitable transparent material. The outer straight edges of each angle arm is provided with graduated scales and also a graduated scale upon the inner straight edge of one of said arms, is provided. These scales are in fractional inches, tenths of inches, and one of the scales in millimeters, as indicated at K, the other scales being indicated by the reference characters S and E, respectively.

To facilitate scale drawings, the end R' of one angle arm is cut away upon a 45° angle and at this point the said arm is also provided with a quarter degree scale. The opposite arm end R'' is cut away at an angle of 30° or 60°, these angles being, in common drafting practice, the most popular.

As noted, the inner edge of one of the angled arms is formed with a plurality of irregular curves I to meet various drawing designs. The face portion of each arm is formed with a series of apertures T of different areas outlining certain geometrical figures, and each figure has extending from its edge quarter markings M, and as indicated by the lines Y—Y and X—X of Figs. 4 and 5. These markings are for the purpose of ascertaining the center of the figures to be drawn.

Such geometrical figures include, for example, circles of various sizes, ellipses, hexagons, squares, triangles and diamonds. It is obvious that these figures may be varied indefinitely.

In practice, when it is desired to form a hexagonal figure, after a certain desired center is indicated upon the drawing paper, the hexagonal aperture of the angle arm is fitted over this center

and a hexagon is produced with a pencil by moving the same around the edges of the aperture. The same method is employed in reproducing all figures.

5 It should be noted that all of the markings, such as squares or the like upon the angle arms, are upon the lower faces of the angle, whereby accurate measurements may be taken without misleading shadows.

10 It should be further noted that the edges of the right angle unit are perpendicular and thick enough to use a ruling ink pen. In practice the abrupt edge is essential when using an inking pen for ruling lines.

15 It is apparent, in the operation of the apparatus, that the angle R may be slid along each track, as indicated in Fig. 2 of the drawings, and also the arms of the angle may be shifted through the throat B', whereby the full scope of the working faces of the angle are obtained.

20 I claim:

A rectangular drafting board, comprising a pair of track-strips secured to the converging edges of the board and terminating at a distance 25 from the intersecting corner of said board, to form a clearance throat for the legs of a triangle, each track-strip being provided with a longitudinal paper receiving recess at its inner face and an aperture communicating with the paper receiving recess, a U-shaped leaf spring having a retaining leg seated under the track-strip and an upper spring leg extending over said track-strip, the same terminating with a downwardly extended paper biting tooth seated in the strip aperture, the said upper spring leg having a keyhole slot therein, a headed stud carried by the drafting board extending upwardly through the leaf spring retaining leg and keyhole slot of the upper leg, and a locking button rotatably mounted upon 30 the headed stud having a rib engageable with the keyhole slot, whereby a sheet of paper is released or clamped to the drafting board.
